CLAIM

We claim the ornamental design for a intraosseous stylet, as shown and described.

DESCRIPTION

FIG. 1 is a front, left perspective view of an intraosseous stylet.

FIG. 2 is a front, right exploded perspective view of the claimed design of FIG. 1;

FIG. 3 is a front elevation view of the claimed design of FIG. 1;

FIG. 4 is a rear elevation view of the claimed design of FIG. 1;

FIG. 5 is a right side view of the claimed design of FIG. 1;

FIG. 6 is a left side view of the claimed design of FIG. 1;

FIG. 7 is a top view of the claimed design of FIG. 1; and,

FIG. 8 is a bottom view of the claimed design of FIG. 1. The broken lines shown in FIGS. 1, 2, and 8 illustrate portions of the intraosseous stylet that form no part of the claimed design.

1 Claim, 5 Drawing Sheets
